UNITED STATES PATENT OFFICE

149,074

DESIGN FOR A CLOSURE FOR BUNG HOLES
OR THE LIKE

Joseph Levine, Flushing, N. Y.

Application December 29, 1945, Serial No. 125,205

Term of patent 3½ years

(Cl. D58—26)

To all whom it may concern:

Be it known that I, Joseph Levine, a citizen of the United States of America, residing in Flushing, Long Island, in the county of Queens, city and State of New York, have invented a new, original, and ornamental Design for a Closure for Bung Holes or the like, of which the following is a specification, reference being made to the accompanying drawing, forming a part thereof.

Fig. 1 is an elevational view of a closure for bung holes or the like embodying my new design;

Fig. 2 is a top plan view thereof; and

Figure 3 is a sectional view taken through line 3—3 of Figure 2 and looking in the direction of the arrows.

I claim:

The ornamental design for a closure for bung holes or the like, substantially as shown.

JOSEPH LEVINE.
